UNITED STATES PATENT OFFICE.

FRANCIS H. BUZZACOTT, OF CHICAGO, ILLINOIS.

DESIGN FOR A RANGE FIRE-DOOR.

SPECIFICATION forming part of Design No. 34,413, dated April 23, 1901.

Application filed March 18, 1901. Serial No. 51,781. Term of patent 7 years.

To all whom it may concern:

Be it known that I, FRANCIS H. BUZZACOTT, a citizen of the United States, residing at Chicago, in the county of Cook and State of Illinois, have invented and produced a new and original Design for a Range Fire-Door, of which the following is a specification, reference being had to the accompanying drawings, forming part hereof.

10 Figure 1 is a view in outer face elevation of a fire-door of my new and original design; Fig. 2, a view of the same in inner face elevation, and Fig. 3 a view taken as indicated at line 3 of Fig. 1.

15 As shown in the drawings, the leading or material feature of my design consists in a flat-plate A, of considerably greater height than width, having a raised outer margin or

periphery a, pivots a' at the lower corners of the door and projecting beyond the vertical edges thereof, locking-lugs a² near the upper end of the door at the vertical edges thereof, and a depression a³, affording a grip for the hand.

Having described my invention, what I claim as new, and desire to secure by Letters Patent, is—

The design for a range fire-door herein shown and described.

In testimony whereof I have signed my name to this specification in the presence of two subscribing witnesses.

FRANCIS H. BUZZACOTT.
